TREATMENT OF HYDROCARBONS

William Alvah Smith, Hamburg, N. Y.

No Drawing. Application March 9, 1938,
Serial No. 194,948

11 Claims. (Cl. 196—31)

This invention relates to the treatment of hydrocarbon compounds and mixtures thereof, including motor and heating plant fuels and lubricating oils, to improve them as to color, composition, properties and characteristics, and more particularly to their treatment for the purpose of removing objectionable impurities therefrom for rendering them more stable in composition and color, and, when the hydrocarbon compounds are lubricating oils, for also reducing the tendency of the oil to sludge or decompose under operating conditions such as in the crank case of an internal combustion engine. Among examples of the impurities which may be readily removed or rendered unobjectionable by this invention may be mentioned sulphur, whether in a combined or uncombined condition, gums and gum forming compounds, and unstable hydrocarbon constituents. Heretofore it has been common practice to partially remove some undesirable impurities, including sulphur compounds, from hydrocarbon compounds and mixtures thereof, including both motor and heating fuels and lubricating oils, some of which hydrocarbon compounds may be unsaturated, by various acidic treating agents such as the mineral acids. Sulphuric acid is the mineral acid or acidic treating agent most commonly used for this purpose, but anhydrous metallic halides, such as aluminum chloride, are acidic treating agents which have also been used for this purpose.

In the usual refining treatment of certain hydrocarbon mixtures, such, for example, as petroleum compounds and particularly the distillates from petroleum cracking stills, it has been found that the unsaturated hydrocarbons in those mixtures or distillates, that is, hydrocarbons containing less than the maximum amount of hydrogen which could be included in the combination, are, to a considerable extent, polymerized into undesirable hydrocarbon compounds, many of which are resinous in character, by the impurities removal agents heretofore employed. Such undesirable compounds when burned in an internal combustion engine are more likely to "knock" or detonate than are the unsaturated compounds before their polymerization.

Frequently these polymerized hydrocarbons have a higher boiling or vaporizing point than is desirable in an internal combustion engine fuel, and therefore are sometimes removed from the desulphurized or treated mixture and discarded, which decreases the yield of marketable fuel obtained from a given quantity of untreated hydrocarbon compounds. The polymerization of un-

saturated compounds into compounds of higher molecular weight is frequently undesirable where the compounds are to be used in chemical reactions. For example, the unpolymerized and unsaturated compounds are usually chlorinated more easily than are saturated and polymerized compounds.

I have discovered that polymerization of the unsaturated compounds can be largely prevented or minimized, the impurities removal action greatly accelerated, and the percentage of impurities removed greatly increased, if the removal action is carried on in the presence of an accelerating or inhibiting agent or substance. According to my discovery, a more desirable product is obtained, and the impurities removal processes may be performed at higher temperatures not heretofore feasible or desirable. Various organic compounds have been found suitable as the accelerating or inhibiting agent, and may be used in the usual methods of removing impurities from hydrocarbon compounds.

The selection of the accelerating or inhibiting agent depends somewhat upon the exact nature of the impurities to be removed, the degrees of unsaturation of the hydrocarbon compounds from which the impurities are to be removed, the amount of impurities to be removed, and the conditions under which the removal is to be performed. In general, I have found that anhydrous treating agents yield better results than those in which water dilution occurs, and when sulphuric acid is used, I have found that in the presence of an inhibiting agent, a concentrated sulphuric acid as near as possible to a one hundred percent pure acid yields more satisfactory results than does commercial oil of vitriol acid, which is usually about ninety-five percent strength.

The amount of the inhibiting agent which it is desirable to use, while varying somewhat with the material to be treated, the impurities to be removed, and the character of the impurities removal agent, is in general less than the molal quantity of the impurities removal agent employed.

When the hydrocarbon compounds to be treated are viscous products, their treatment may be facilitated by first reducing their viscosity, either by heating the same first to reduce the viscosity or by mixing therewith the necessary amount of a thin liquid such as, for example, gasoline, which viscosity reducing addition agent, such as gasoline, can be removed readily by volatilization or

other refinery practice after the impurities removal treatment has been completed.

Among the various inhibiting agents which may be satisfactorily employed may be mentioned the aryl nitro and nitroso compounds including the true aryl nitro compounds where the NO_2 group is attached directly to a benzene ring, and the aryl nitroso compounds. The following are outstanding examples of true aryl nitro compounds that I have found to be very satisfactory inhibitors and accelerators in accordance with this invention:—nitro benzene, o-nitro benzoic acid, m-di nitro benzol, m-nitro aniline, p-nitro aniline, o-nitro phenol, p-nitro phenol, 2-nitro diphenyl, 1.8 nitro naphthalene, 2.4-di nitro aniline, 1.3.5 tri nitro benzol, 1.2.4.6 tri nitro phenol, picramic acid, picramide or sym. tri nitro aniline, 2.4 di nitro phenol, and the nitro-toluenes.

The following are outstanding examples of aryl nitroso compounds that I have found to be very satisfactory as inhibitors and accelerators in accordance with this invention:—di nitroso resorcinol and p-nitrosodimethylaniline and nitroso benzenes.

The inhibiting agent may be added either to the impurities removal agent before the latter is added to the hydrocarbon mixtures, or to the hydrocarbon mixture before the impurities removal agent is added to the hydrocarbon mixture. I prefer to add the inhibiting agent to the hydrocarbon mixture first, and then add the impurities removal agent to this combined mixture, and the improved method of treatment may be of either the continuous or batch type.

After the hydrocarbon compounds or mixtures thereof have been treated with the impurities removal agent and the inhibiting agent, the complete mixture may be agitated continuously until the reaction is complete. The reaction I have found is usually completed within about ten minutes when the acid treatment is used for the removal of sulphur, and within approximately one half hour if a metallic halide is used as the removal agent. After the reaction is complete, the combined mixture is left quiescent, whereupon the residue separates out carrying the impurities and the treating agent, which then may be removed in any suitable manner such as by draining off the supernatant liquid, or by treatment with fuller's earth or other adsorbent material, or by washing with water. This treated material may then be subjected to any further neutralization or treatment as desired to finish it for the market and to remove any viscosity reducing agent. The residue may be then disposed of as usual in the industry, or treated for the recovery of any valuable components thereof.

Without the use of the inhibiting agent or material, the acidic impurities removal treatment often required several hours or days in order to get a high percentage of removal of the impurities. The use of the inhibiting agent also speeds up the reaction and makes the removal of impurities more complete, without undesirable polymerization or alteration of the hydrocarbons. I have found that by the use of the inhibiting agent, the action is more rapid at the same temperatures, and one may use higher temperatures during the removal reaction in order to speed up the reaction without materially increasing the polymerization of the unsaturated compounds, which polymerization or alteration always heretofore occurred to a very great extent whenever the impurities removal reaction was speeded up by the use of the higher temperatures.

Removal of impurities with such an inhibiting agent may be applied to hydrocarbon mixtures in any stage of refinement or in crude form, and produces a product which I have found will stand exposure to light more satisfactorily than products obtained by similar removal processes without the use of the inhibitor. The removal of sulphur, for example, when accomplished in the presence of the inhibitor, is more complete for a given amount of the sulphur removing agent than is possible without the use of an inhibitor, and the inhibitor may be used without any change in the apparatus used heretofore for sulphur removal. The amount of acidic treating agent can be increased to the desired point, impractical otherwise, in order to secure desired refining results. For example, in treating Pennsylvania lubricating oils, such quantities of 98% sulphuric acid as 30 pounds per barrel or more can be used successfully and to advantage without excessive loss of the lubricating material itself.

When motor fuels, such as gasolines, are treated in accordance with this invention, the resulting product is non-corrosive, lower in gum content, very much more stable as evidenced by the distillation test residues which are relatively light colored, and has better color and color stability. When heavier petroleum products such as lubricating oils are treated in accordance with this invention, the color, non-corrosiveness, tendency to "sludge" or decompose under operating conditions, particularly under the conditions existing in the crank cases of internal combustion engines, and the resistance to heat are improved in a similar manner. I have also discovered that lubricating oils intended for use in automotive engine lubrication can be given still greater color stability and resistance to sludging by the admixture with the oil of the desired, and preferably a relatively small, amount of quinhydrone. When the quinhydrone is used even in such small amounts as .001% by weight, the results have been found satisfactory and effective in some cases, but usually a larger percentage of the quinhydrone is preferred up to a percentage which is soluble in the oil.

In the foregoing description, reference has been made to sulphur as one of the impurities that may be removed or rendered unobjectionable in accordance with this invention, but it will be understood that the exact composition of the impurities which are found in petroleum hydrocarbons is not definitely known, but sulphur is one of the major impurities found in such petroleum products which can be removed or rendered unobjectionable by this invention. It is also believed that the removal of undesirable nitrogen compounds is facilitated by this invention.

This application is, in part, a continuation of my copending application Serial No. 431,990, filed February 27, 1930.

I claim as my invention:

1. In the refining of petroleum hydrocarbons, the improvement which comprises reducing the viscosity where necessary, and then subjecting the product at the same time to the action of sulphuric acid and an aryl nitro in which the NO_2 group is attached directly to a benzene ring.

2. The method of treating petroleum lubricating oils to increase their color stability, to remove impurities, and to reduce corrosiveness and the tendency to sludge and decompose under storage and operating conditions, which comprises treating such oils at the same time with sulphuric acid and an aryl nitro compound in which the

NO₂ group is attached directly to a benzene ring.

3. The method of treating petroleum compounds including both lubricating oils and motor and heating plant fuels to increase their color stability, to remove impurities, and to reduce corrosiveness and the tendency to sludge and decompose under storage and operating conditions, which comprises treating such petroleum compounds at the same time with a mineral acid and an aryl nitro compound in which the NO₂ group is attached directly to a benzene ring, in which treatment the nitro compound is added to the petroleum compound at least as early as said mineral acid.

4. The method of treating petroleum compounds including both lubricating oils and motor and heating plant fuels to increase their color stability, to remove impurities, and to reduce corrosiveness and the tendency to sludge and decompose under storage and operating conditions, which comprises treating such petroleum compounds at the same time with a mineral acid and an aryl nitro compound in which one or more hydrogen atoms of a benzene nucleus or condensed benzene nuclei are replaced with NO₂, but in which the amount of the inhibiting compound is in general less than approximately the molal quantity of the sulphur removal agent.

5. The method of treating petroleum compounds including both lubricating oils and motor and heating plant fuels to increase their color stability, to remove impurities, and to reduce corrosiveness and the tendency to sludge and decompose under normal storage and operating conditions, which comprises treating such petroleum compounds at the same time with concentrated sulphuric acid and an aryl nitro compound in which one or more hydrogen atoms of a benzene nucleus or condensed benzene nuclei are replaced with NO₂.

6. The method of treating petroleum compounds including both lubricating oils and motor and heating plant fuels to increase their color stability, to remove impurities, and to reduce corrosiveness and the tendency to sludge and decompose under storage and operating conditions, which comprises first adding to such petroleum compounds and an aryl nitro compound in which one or more hydrogen atoms of a benzene nucleus or condensed benzene nuclei are replaced with NO₂, then adding concentrated sulphuric acid, agitating the mixture until the reaction is complete, and then separating out and discarding the solids carried in suspension.

7. The method of treating petroleum compounds including both lubricating oils and motor and heating plant fuels to increase their color stability, to remove impurities, and to reduce corrosiveness and the tendency to sludge and decompose under storage and operating conditions, which comprises treating such petroleum compounds at the same time with a mineral acid and an aryl nitro compound in which one or more hydrogen atoms of a benzene nucleus or condensed benzene nuclei are replaced with NO₂.

10 8. The method of treating petroleum compounds including both lubricating oils and motor and heating plant fuels to increase their color stability, to remove impurities, and to reduce corrosiveness and the tendency to sludge and decompose under storage and operating conditions, which comprises treating the entire body of such petroleum compounds at the same time with a mineral acid and an aryl nitro compound in which the NO₂ group is attached directly to a benzene ring.

15 9. In refining hydrocarbon mineral oil for the removal of sulphur and other impurities, the improvement which comprises subjecting the oil to the action of nitro-benzene and sulphuric acid at the same time.

20 10. In the refining of hydrocarbon mineral oil for the removal of sulphur and other impurities, the improvement which comprises adding to the oil first a minor quantity of nitrobenzene, and then adding sulphuric acid to the mixture thereof, whereby the oil will be subjected to the action of the nitrobenzene and sulphuric acid at the same time, and in which the amount of nitrobenzene is less than approximately the molal quantity of the sulphuric acid used.

25 11. In the refining of petroleum compounds including lubricating oils and motor and heating plant fuels to increase their color stability, to remove impurities and to reduce corrosiveness and tendency to sludge and decompose under storage and operating conditions, that improvement which comprises treating said compounds at the same time with an aryl nitro compound in which one or more hydrogen atoms of a benzene nucleus or condensed benzene nuclei are replaced with NO₂, and a concentrated mineral acid and agitating the mixture, and in which the amount of the aryl nitro compound is in general less than approximately the molal quantity of the mineral acid used.
